DISPLAY-TYPE LIGHTING FIXTURE FOR INDOOR
AND OUTDOOR USE SUCH AS PATIOS AND
THE LIKE

Alfred A. Campana, 101 Westminster Ave.,
Merchantville, N.J. 08109

Filed Aug. 9, 1967, Ser. No. 8,185

Term of patent 14 years

Int. Cl. D26—02

U.S. Cl. D48—20

FIGURE 1 is a front elevational view of a display-type lighting fixture for indoor and outdoor use such as patios and the like showing minute design;

FIGURE 2 is a side elevational view thereof;

FIGURE 3 is a rear elevational view thereof.

The dominant features of my design reside in the portions shown in full lines.

The ornamental design for a display-type lighting fixture for indoor and outdoor use such as patios and the like, as shown and described.
